(57) **CLAIM**

The ornamental design for a rotary atomizer component, as shown and described.

DESCRIPTION

FIG. 1 is an upper perspective view of a rotary atomizer component showing our new design;

FIG. 2 is a top view thereof;

FIG. 3 is a side view thereof;

FIG. 4 is another side view thereof;

FIG. 5 is a bottom view thereof;

FIG. 6 is a rear view thereof; and,

FIG. 7 is a front view thereof.

The broken lines in the FIGS. are directed to environment and are for illustrative purposes only. The broken lines form no part of the claimed design.
